(57) **CLAIM**

The ornamental design for a trap for rodents, in particular for mice and rats, as shown and described.

DESCRIPTION

FIG. 1 is a side, top and front perspective view of the trap for rodents, in particular for mice and rats;

FIG. 2 is a side, top and front perspective view of FIG. 1 showing the trap in a position of rest;

FIG. 3 is a top plan view thereof; and,

FIG. 4 is a bottom plan view thereof.

The drawings relate to two designs and are showing views of a trap for rodents, in particular for mice and rats, and a double entrance, tunnel-like trap housing in form of a bait box with two such traps fixed in the housing.
